UNITED STATES PATENT OFFICE.

FRANK ROE BATCHELDER, OF WORCESTER, MASSACHUSETTS, ASSIGNOR TO MILLS WOVEN CARTRIDGE BELT COMPANY, OF WORCESTER, MASSACHUSETTS, A CORPORATION OF MASSACHUSETTS.

WOVEN STRAP.

1,147,135.

Specification of Letters Patent.

Patented July 20, 1915.

Application filed March 23, 1908. Serial No. 422,812.

To all whom it may concern:

Be it known that I, FRANK ROE BATCHELDER, a citizen of the United States, residing at Worcester, in the county of Worcester, 5 State of Massachusetts, have invented a certain new and useful Improvement in Woven Straps, of which the following is a specification, reference being had therein to the accompanying drawings.

10 The invention has reference more particularly to shoulder-straps, such for instance as those forming part of the suspenders pertaining to military equipments, or the single straps from which a haversack, 15 canteen, traveling bag, or other article may be suspended. It is applicable, as well, to other straps having broad portions like that which in the case of a shoulder-strap rests upon the shoulder of the user, and provided 20 with narrow portions at the ends of such broad portions for connection or engagement with the articles or things to be suspended or secured.

The invention consists in a strap of woven 25 material comprising a main portion composed of a broad strap-web and a narrow strap-portion combined together, with one end of said narrow strap-portion confined within the thickness of the broad strap-web, 30 and having the end-portion of the said broad strap-web narrowed or tapered in new and improved manner producing uncut or finished edges on the narrowed or tapered portion.

35 My present invention enables me to produce an improved strap having broad and narrow portions partly by weaving and partly by subsequent operations, and while the fabric or web is not strictly continuous, 40 that is, having the broad and narrow portions integral with each other, it nevertheless presents the appearance of being such.

In the drawings, —Figure 1 shows in plan a strap embodying the invention. Fig. 2 is 45 an edge view thereof. Fig. 3 is a top or plan view of a length of the broad strap-webbing, in the state in which it is produced as woven. Fig. 4 is a view showing a portion of the length of the strap-webbing of 50 Fig. 3, in longitudinal vertical section. Fig. 5 is a top or plan view of the portion of strap-webbing that is shown in Fig. 4 and an added narrow strap-portion, illustrating the manner of tucking the marginal portions

of the disunited plies to produce the narrowing. Fig. 6 is a view in cross-section on line 6, 6, of Fig. 5. Fig. 7 illustrates a slight modification in the narrowing. Figs. 8 and 9 show webbings of modified weaves.

In conformity with the invention, I provide for the broad portion of a strap a broad webbing which presents at an end thereof upper and lower plies 1^a, 1^a, Figs. 4, 6, 8 and 9, that are disunited from each other transversely across the width of such webbing. The plies 1^a, 1^a, are respectively of partial thickness, as represented. By "partial thickness" I intend herein the fact that each of the said plies 1^a, 1^a, forms only a part or portion of the entire thickness of 70 the webbing. Preferably, the adjoining portion 1^b of the length of the broad webbing is composed of continuations of the said plies, as shown in Fig. 4, although in Fig. 8 in the portion therein marked 1^b, the warp-threads extend from surface to surface and the plies are merged in what is practically a single-ply weave. Preferably, also, though not necessarily in all cases, the said adjoining portion is solid or substantially 80 solid fabric. This is produced in the weaving, when the said portion is composed of different plies, as in Fig. 4, by binding the said plies together in some approved manner of interweaving warp and weft-threads, 85 or by some such weave as that shown in Fig. 8. In Figs. 1, 3 and 5 the plies are bound together along lines indicated at 1^c, 1^c, etc., and Fig. 4 illustrates the use of binder-warps 1^d, 1^d, etc., crossing back and 90 forth between the two plies. The precise way in which the interweaving or binding together is effected is not material. If it is not required that the said adjoining portion be solid, the binder-warps may be omitted, 95 as at 1^d in Fig. 9, in which case the plies will be separate, except along the edges of such portion, where they are united by weft passing from one ply to the other as usual in weaving flattened tubular goods.

The broad webbing is, for convenience, produced by weaving the same practically as a flattened hose; that is to say, it is woven in upper and lower plies which are joined together at the opposite margins of 105 the webbing by the continuous weft or filling passing at the said margins from one ply to the other, but except in the case of

the web of Fig. 9 the said plies are bound together into substantially solid fabric throughout the intermediate or main portion of the webbing. The end-portion, 5 however, are in the form of flattened tubes. In the production of the said webbing, it is woven in a continuous strip, in which except in the case of the web of Fig. 9 solid fabric and flattened tubular fabric alternate, as, for instance in Fig. 3. This strip is separated into strap-portions by cutting across the same at each length of flattened tube. The flattened tubular web of Fig. 9 is likewise cut across at suitable points to 15 form the desired broad strap-portions.

Taking in hand a strap-portion I turn or truck the marginal portions of the disunited plies inwardly between the middle portions of the width of such plies, in the manner 20 illustrated in Fig. 6 or that illustrated in Fig. 7. In thus turning-in or tucking the said marginal portions, I do so in such manner as to cause the webbing to taper or narrow as in Figs. 1 and 5, to a width corresponding with that of the narrow strap-portion 2, which is to be combined therewith, thus producing a suitably-narrowed tab-junction. In the present instance this 25 may be assumed to be one inch. I may slit the said marginal portions as in Fig. 6 or leave them unslitted as in Fig. 7, or cut away the excess of material. For the purpose of connecting the narrow strap-portion 2 (it having a width of an inch, for instance) with the broad strap-portion, I insert one end of such narrow strap-portion between the plies as in Figs. 5 and 6, or as 30 in Fig. 7 and then securely fasten the different layers together by lines of stitches, as 35 at 11, 11, Fig. 1, extending along the side-edges of the narrowed portion and also across the same. After being stitched, the 40 end-portion of the broad strap-portion is pressed or ironed and thereby flattened out 45 and reduced in thickness to approximately the same thickness as other portions of the broad strap-portion.

For greater security, as well as to give a 50 neat finish to the article, I may, and preferably do, pass over the narrow strap-portion 2 a metal clasp or shield 12, Figs. 1, 2. This latter is shown tapered in width to fit the taper of the narrowed portion of the broad strap-portion, and is also tapered

from its large end, where the opening is proportioned to suit the greater thickness of assembled layers, to its small end, where the opening is proportioned to suit the smaller thickness of the narrow strap-portion 2. By means of a substantial rivet 13, this 55 shield or clasp is fixed firmly in position at the same time uniting the broad and narrow strap portions in such manner that they could not separate, even should the stitching give way. 60

As a result of turning-in or tucking the marginal portions of the plies 1^a, 1^a, I form uncut or finished edges 1^e, 1^e, upon the narrowed parts of the broad strap-portion. 65

I claim as my invention:—

1. A woven strap comprising a main portion composed of continuous upper and lower plies woven unitedly in a seamless webbing and a separate narrower piece having an end thereof confined between the 70 said plies, with the margins of said plies inwardly tucked at the end of the broad portion forming a tapering narrowed section with finished edges, and having all the layers fastened together in said tapering 75 section.

2. A woven strap comprising a main portion of substantially solid woven fabric-structure having an end thereof in disunited plies of partial thickness, and a separate 80 narrower piece with one end thereof confined between the said plies, with the margins of said plies inwardly tucked forming a tapering narrowed section with finished 85 edges, and having all the layers fastened together in said tapering section. 90

3. A woven strap comprising a main portion composed of continuous upper and lower plies woven unitedly in a seamless webbing, and a separate narrower piece having an end thereof confined between said plies, and with the margins of the said plies inwardly tucked at the end of the broad portion so as to form a tapering narrowed section with finished edges, and a fitting 95 which clasps and incloses the narrow extremity of said tapering section. 100

In testimony whereof I affix my signature in presence of two witnesses.

FRANK ROE BATCHELDER.
